CLAIM

The ornamental design for a plenum and nozzles module for patient interface, as shown and described.

DESCRIPTION

FIG. 1 is a front perspective view of a plenum and nozzles module for patient interface showing an embodiment according to our new ornamental design;

FIG. 2 is an enlarged perspective view thereof in isolation;

FIG. 3 is a front view thereof;

FIG. 4 is a rear view thereof;

FIG. 5 is a top view thereof;

FIG. 6 is a bottom view thereof;

FIG. 7 is a right side view thereof;

FIG. 8 is a left side view thereof;

FIG. 9 is a rear perspective view thereof;

FIG. 10 is a front perspective view of a plenum and nozzles module for patient interface showing an embodiment according to our new ornamental design;

FIG. 11 is an enlarged perspective view thereof in isolation;

FIG. 12 is a front view thereof;

FIG. 13 is a rear view thereof;

FIG. 14 is a top view thereof;

FIG. 15 is a bottom view thereof;

FIG. 16 is a right side view thereof;

FIG. 17 is a left side view thereof;

FIG. 18 is a rear perspective view thereof;

FIG. 19 is a front perspective view of a plenum and nozzles module for patient interface showing an embodiment according to our new ornamental design;

FIG. 20 is an enlarged perspective view thereof in isolation;

FIG. 21 is a front view thereof;

FIG. 22 is a rear view thereof;

FIG. 23 is a top view thereof;

FIG. 24 is a bottom view thereof;

FIG. 25 is a right side view thereof;
